CYLINDRICAL GRINDING MACHINE

Herbert A. Silven, Worcester, Mass., assignor to
 Norton Company, Worcester, Mass., a corpora-
 tion of Massachusetts

Application November 21, 1945, Serial No. 630,045

12 Claims. (Cl. 51—95)

1

The invention relates to grinding machines and more particularly to an electrically operated cylindrical grinding machine.

One of the objects of this invention is to provide a simple, thoroughly practical, readily controllable, electrically driven cylindrical grinding machine. Another object is to provide a cylindrical grinding machine with a variable speed table reciprocating mechanism which is arranged so that independently adjustable speeds may be obtained for grinding and for truing which may be readily shifted from grinding to a truing speed and vice versa without disturbing the independent speed adjustments.

Another object of the invention is to provide an electric table driving mechanism including a variable-speed reversing motor and a gear driving mechanism including a pair of clutches arranged to reciprocate the grinding machine table at a relatively slow speed for a grinding wheel truing operation. Another object of the invention is to provide such a machine with independent adjusting control mechanism including potentiometers to control the speed of the motor so as to produce either a relatively high speed of the table for a traverse grinding operation or a relatively slow speed of the table for a truing operation. Another object of this invention is to provide means including a control lever for readily shifting from a grinding to a truing speed of the table in which the control lever is arranged to shift not only the clutches but also to actuate a transfer switch so as to render either a grinding speed potentiometer or a truing speed potentiometer operative.

A further object of the invention is to provide a table dwell control mechanism for causing an adjustable dwell at both ends or either end of the table stroke including a pair of independent electric time dwell relays for controlling the period of dwell as desired. Another object of the invention is to provide means including a switch actuated by the control lever to render both of the electric timers inoperative when the control lever is shifted to a truing position so as to render the dwell control mechanism inoperative during a grinding wheel truing operation.

A further object of the invention is to provide a feeding mechanism including a clutch actuated pawl and ratchet mechanism which is arranged to either continuously reciprocate said pawl for a plunge-cut grinding operation or to intermittently actuate the pawl at the ends of the table stroke for a truing operation. Other objects will be apparent from the foregoing disclosure.

2

This invention accordingly consists in the features of construction, combinations of elements, and arrangements of parts as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of a cylindrical grinding machine embodying the invention;

Fig. 2 is an electrical wiring diagram of the table driving mechanism;

Fig. 3 is a vertical section view partly in elevation taken approximately on the line 3—3 of Fig. 4 combined with an electrical wiring diagram of the wheel feed control mechanism;

Fig. 4 is a fragmentary vertical sectional view, on an enlarged scale, taken approximately on the line 4—4 of Fig. 1 through the wheel feeding mechanism;

Fig. 5 is a fragmentary front elevation, on an enlarged scale, showing the manual table traverse mechanism, the reversing lever and main control lever;

Fig. 6 is a fragmentary plan view, on an enlarged scale, of the parts and mechanisms shown in Fig. 5;

Fig. 7 is a plan view of the table reversing switch;

Fig. 8 is a fragmentary vertical sectional view, on an enlarged scale, taken approximately on the line 8—8 of Fig. 5, through the manual table traverse mechanism;

Fig. 9 is a vertical sectional view, on the enlarged scale, taken approximately on the line 9—9 of Fig. 5 through the table control lever and mechanism;

Fig. 10 is a fragmentary vertical sectional view, on an enlarged scale, of the table driving mechanism;

Fig. 11 is a development of the feed mechanism clutch and cam, showing the position of the cam and follower at the left hand end of the table stroke;

Fig. 12 is a development of the feed mechanism clutch and cam, showing the position of the cam and follower at the right hand end of the table stroke;

Fig. 13 is a fragmentary sectional view, on an enlarged scale, of the eccentric stud for shifting the table drive clutches;

Fig. 14 is a fragmentary cross sectional view, on an enlarged scale, taken approximately on the line 14—14 of Fig. 9;

Fig. 15 is a fragmentary horizontal sectional view, on an enlarged scale, showing the connections between the start and stop lever and the clutch for controlling the manual traverse;

Fig. 16 is a horizontal sectional view taken approximately on the line 16—16 of Fig. 5, through the control lever mechanism;

Fig. 17 is a horizontal sectional view taken approximately on the line 17—17 of Fig. 5;

Fig. 18 is a fragmentary vertical sectional view, on an enlarged scale, taken approximately on the line 18—18 of Fig. 5, through the table reversing lever;

Fig. 19 is a fragmentary vertical sectional view, on an enlarged scale, taken approximately on the line 19—19 of Fig. 6;

Fig. 20 is a fragmentary vertical sectional view, taken approximately on the line 20—20 of Fig. 9, through the control lever mechanism;

Fig. 21 is a fragmentary cross sectional view, on a reduced scale, taken approximately on the line 21—21 of Fig. 15 through the latch mechanism;

Fig. 22 is a fragmentary cross sectional view, taken approximately on the line 22—22 of Fig. 20;

Fig. 23 is a fragmentary cross sectional view, on an enlarged scale, through the feed wheel; and

Fig. 24 is an electric wiring diagram of the Thy-Mo-Trol electronic motor control apparatus and other electric control apparatus associated therewith.

A grinding machine has been illustrated in the drawings comprising a base 10 having a longitudinally reciprocable table 11 mounted thereon on the usual flat way 12 and V-way 13. The table 11 serves as a support for a rotatable work piece comprising a head stock 14 having a head stock center 15 and a foot stock 16 having a foot stock center 17. The head stock center 15 and foot stock center 17 are arranged rotatably to support a cylindrical work piece 18 for a grinding operation.

The head stock 14 is preferably a motor driven head stock comprising a variable-speed reversible electric motor 19 mounted on the upper surface of the head stock 14. Push button switches 20 and 21 are provided on the front of the machine base 10 for starting or stopping the motor 19 as desired. A speed control device 22, such as a rheostat, is provided for controlling the speed of the work drive motor 19. A reversing switch 23 is also provided for changing the direction of the rotation of the motor 19 when desired. A jogging switch 24 is provided on the front of the machine base which is operatively connected so that the work drive motor 19 may be jogged to position the work when desired.

A transversely movable slide 30 is mounted on transversely arranged V-way 31 and a flat way 32. The wheel slide 30 is provided with a rotatable wheel spindle (not shown) for supporting a rotatable grinding wheel 33. The wheel 33 and its supporting spindle are driven by means of an electric motor 34 which is mounted on the upper surface of the wheel slide 30. The motor 34 is provided with an armature shaft 35 which supports a multi-V-grooved pulley 36 which is connected by means of multiple V-belts 37 with a multi-V-grooved pulley 38 which is mounted on the right hand end of the wheel spindle (not shown).

A manually operable traverse mechanism is provided for traversing a work supporting table 11 which comprises a manually operable traverse

wheel 40. The traverse wheel 40 is rotatably mounted on a stud 41 which is fixed relative to the base 10. A gear 42 is keyed to rotate with the hand wheel 40. The gear 42 meshes with a gear 43 which is rotatably mounted on a stud 44. The gear 43 meshes with a gear 45 which is rotatably supported by means of a ball bearing 46. The gear 45 is provided with an inwardly projecting sleeve which is provided at its inner end with clutch teeth 47. A rotatable shaft 48 is rotatably journaled within a bushing supported by the gear 45 and at its other end by means of a ball bearing 49. A slidably mounted clutch member 50 is slidably keyed with shaft 48 so that it may be moved into or out of engagement with the clutch teeth 47. A pivotally mounted yoked lever 51 is mounted on the lower end of a rock shaft 52. The yoked arm 51 is provided with diametrically opposed studs which ride in a groove formed in the clutch member 50. An actuated lever 53 is fixedly mounted on the upper end of the rock shaft 52 by means of which the clutch member 50 may be actuated. The lever 53 is arranged to be automatically actuated in timed relation with the power traversing mechanism for the table in a manner to be hereinafter described.

The shaft 48 is provided at its inner end with a bevel gear 55 which meshes with a bevel gear 56. The bevel gear 56 is keyed to a rotatable shaft 57. A worm 58 is formed integral with the shaft 57 and meshes with a worm gear 59 which is keyed on a projecting hub of a gear 60 (Fig. 8). The gear 60 is keyed to a rotatable shaft 61 which is journaled in anti-friction bearings 62 and 63. The gear 60 meshes with a rack bar 64 which is fixedly mounted on the under side of the table 11.

A power operated mechanism is provided for reciprocating the work table for a traverse grinding operation. This mechanism preferably comprises a variable-speed reversible motor 70 (Figs. 4 and 10). The motor 70 is provided with an armature shaft 71 which is keyed within an integral hub of a gear 72 (Fig. 10). The gear 72 is supported by anti-friction bearings 73 and 74 which are in turn supported in a casing 75 which is fixed relative to the base 10.

The gear 72 meshes with a gear 76 which is supported on a rotatable stud 77. The stud 77 is rotatably supported by anti-friction bearings 78 and 79 which are in turn supported by the casing 75. The gear 76 meshes with a gear 80 which is mounted on the right hand end of a rotatable shaft 81. The shaft 81 is journaled in anti-friction bearings 82, 83 and 84 which are supported in a casing 85 which is fixed relative to the base 10. The shaft 81 is connected by means of a flexible coupling 86 with a shaft 87.

In a cylindrical grinding machine it is desirable to provide a speed control mechanism for the work table so that it may be traversed either at a desired range of relatively high speeds for a grinding operation or at a very slow speed for a grinding wheel truing operation. The electric motor 70 is a variable speed reversible motor which combined with the control mechanism to be hereinafter described may be adjusted to provide a wide range of speeds to the table 11. In order to supplement the electrical speed changes for the table 11, it may be desirable to provide a change gear mechanism whereby the speed of the table may be adjusted so as to provide either a fast or a slow reciprocating speed independent of the motor 70.

In the preferred construction, a gear driving

mechanism is provided between the shaft 87 and the worm shaft 57. The shaft 87 is journalled in a ball bearing 88 at one end and in a bushing 89 at its other end. The bushing 89 is mounted in a hollow end portion of the worm shaft 57. The worm shaft 57 is supported in ball bearings 90 and 91 which are in turn supported in a casting fixed relative to the base 10. A gear 92 is keyed to the shaft 87 and meshes with a gear 93 which is supported by anti-friction bearings 94 and 95. The bearings 94 and 95 are in turn supported on a rotatable shaft 86. The shaft 96 is supported at its opposite ends by ball bearings 97 and 98. The gear 93 is provided with clutch teeth 99 which are arranged to be engaged by a slidably mounted clutch member 100 which is rotatably supported by an anti-friction bearing 101. The anti-friction bearing 101 is supported by a slidably mounted clutch casing 102. The clutch member 100 is slidably keyed to a sleeve 103 which is in turn keyed to the shaft 96. A gear 104 is formed integral with the sleeve 103 and meshes with a gear 105. The gear 105 is fixedly connected to the worm shaft 57 by means of a pin 106. Clutch teeth 107 are either formed integral with or fixedly mounted relative to the gear 105. A slidably mounted clutch member 108 is slidably keyed to a sleeve formed integral with the gear 92. The clutch member 108 is supported in a ball bearing 109 carried by the clutch casing 102.

It will be readily apparent from the foregoing disclosure that if the clutch member 108 is moved toward the left (Fig. 10) into engagement with the clutch teeth 107 the shaft 87 will be connected directly to the worm shaft 57 and will drive the worm 58 at the same speed as the shaft 87 so as to transmit a relatively fast reciprocatory movement to the table 11. If it is desired to change the speed of the table 11 to a slow truing speed, the clutch casing 102 may be moved toward the right (Fig. 10) to move the clutch member 100 into engagement with the clutch teeth 99 so that the rotary motion of the shaft 87 will be transmitted through the gear 92, the gear 93, the gear 104 and the gear 105 to rotate the worm shaft 57 and the worm 58 at a relatively slow speed during a truing operation.

It is desirable to provide a readily accessible means for shifting the clutch casing 102 to engage either of the clutches when desired. This mechanism may comprise a rotatable shaft 110 which is journalled in an aperture 111 which is fixed relative to the base 10. The shaft 110 is provided at its left hand end (Fig. 9) with an eccentric stud 112 which meets with and engages a hole formed in a slide block 113. The slide block 113 is slidably supported in a groove 114 formed in the clutch casing 102. A manually operable control lever 115 is provided for rocking the shaft 110 to shift the clutch casing 102 as desired. The lever 115 is preferably pivotally supported on a dial shaped member 116 by means of a stud 117.

It is desirable to provide a yieldable connection between the control lever 115 and the shaft 110 to assist in throwing the clutch members into engagement in case the clutch teeth do not line up at the time the clutch casing 102 is shifted. This mechanism preferably comprises a collar 118 which is fixedly mounted on the right hand end of the shaft 110 (Fig. 9). The collar 118 is provided with two spaced upwardly extending lugs 119. A downwardly extending lug 120 is fixedly supported relative to the dial 116 and

extends within the space formed between the lugs 119. A circular or ring shaped spring 121 engages opposite sides of the lugs 119 and the lug 120 (Fig. 14). It will be readily apparent from the foregoing disclosure that when the lever 115 is shifted in either direction to shift the clutch casing 102 into either a grinding or a truing position, the spring 121 will provide a yieldable connection in case the clutch teeth do not align each other with the mating clutch teeth so as the shaft rotates the clutch teeth into alignment, the released compression of the spring 121 will throw the clutch casing 102 to engage the clutch member as desired.

15 A grinding wheel feeding mechanism is provided for feeding the grinding wheel 33 and its supporting wheel slide transversely toward and from the work piece 18. This mechanism is preferably arranged so that the grinding wheel may be fed manually, or may be fed continuously by means of a continuous reciprocated picker pawl for a plunge-cut grinding operation or be fed intermittently at the ends of the table stroke for a traverse grinding operation. A 20 wheel feeding mechanism has been illustrated comprising a rotatable feed screw 125 which meshes with a half nut 124 depending from the under side of the wheel slide 30. The feed screw 125 is provided with a reduced end portion 126 which is slidably keyed within an aperture 127 formed in a hollow end portion 128 of a rotatable shaft 129. The shaft 129 is rotatably supported in bearings 130 and 131 which are in turn fixedly supported relative to the base 10. A gear 25 132 is mounted on the right hand end of the shaft 129 (Fig. 4). The gear 132 meshes with a small gear 133 which is arranged to rotate with a manually operable feed wheel 134. The feed wheel 134 is rotatably supported on the front of the machine base and is provided with a micrometer feed adjusting mechanism 135 and a stop abutment 136. It will be readily apparent from the foregoing disclosure that by manually rotating the feed wheel 134 the screw 125 may be rotated in either direction to cause a forward or a rearward movement of the grinding wheel slide 30.

30 A power operated mechanism is provided for actuating the feed wheel 134 comprising a gear 50 or ratchet wheel 137 and a feed picker pawl 138. The feed pawl 138 is pivotally supported by means of a stud 139 on a pivotally mounted arm 140. A power shaft 141 is provided in the base of the machine. A crank plate 142 is fixedly mounted on the front end of the shaft 141. An adjustable crank pin 143 is adjustably supported by a T-slot formed in the crank plate 142. A connecting rod 145 is connected to the pin 143 at its lower end and by means of a stud 146 carried by the arm 140 at its upper end. The shaft 141 is supported in bearings 150 and 151 which are fixedly mounted within the base 10.

35 The power shaft 81 is provided with a spiral gear 152 which meshes with a spiral gear 153. The spiral gear 153 is rotatably supported on the shaft 141. Clutch teeth 154 are either formed integral with or fixedly mounted relative to the spiral gear 153. A slidably mounted clutch member 155 is slidably keyed to the shaft 141. A compression spring 156 normally serves to hold the clutch member 155 in engagement with the clutch teeth 154 so that a rotary motion of the shaft 81 will be transmitted through the spiral gears 152 and 153 to rotate the shaft 141 continuously. Continuous rotation of the shaft 141

will impart a continuous revolving movement of the crank pin 143 which in turn transmits an oscillating movement to the feed pawl 138 to cause a continuous intermittent rotation of the feed wheel 134 to impart a continuous infeeding movement to the grinding wheel for a plunge-cut grinding operation.

In order to provide an intermittent feeding movement of the grinding wheel at the ends of table stroke, a suitable mechanism is provided for de-clutching the clutch member 155. This mechanism preferably comprises a cam 157 which is formed integral with the clutch member 155. A slidably mounted cam follower 158 is slidably supported and is actuated by a rock arm 162 (Fig. 3). A tension spring 160 is connected to the other end of the rock arm 162 and is arranged normally to hold the follower 158 in operative engagement with the cam 157. A solenoid 161 (Figs. 3 and 4) is operatively connected to actuate the rock arm 162 and is arranged when energized to move the cam follower 158 upwardly (Fig. 3) against the tension of the spring 160. The released compression of the spring 156 moves clutch member 155 into engagement with the clutch teeth 154 to rotate the shaft 141 continuously so as to impart a continuous reciprocatory movement to the feed pawl 138 for a plunge-cut grinding operation. In order to produce an infeeding movement at the ends of the table stroke, the solenoid 161 is operatively connected in a manner to be hereinafter described so that the solenoid 161 will be energized at the ends of the table stroked during reversal to produce an intermittent infeeding movement of the grinding wheel or a transverse grinding operation.

A manually operable start and stop lever 165 is fixedly mounted on the upper end of a vertical rock shaft 166. The lower end of the rock shaft 166 supports a projecting arm 167 which is connected by means of a stud 168 with a link 169. The other end of the link 169 is connected by a stud 170 with a rock arm 171. The rock arm 171 is pivotally supported on a stud 172. The rock arm 171 is arranged when rocked to actuate a stop switch 173 and a start switch 174. When it is desired to start the machine, the start and stop lever 165 is rocked in a counterclockwise direction (Figs. 6 and 15) into broken line position 165a. This movement serves to rock the shaft 166 and the arm 167 in a counterclockwise direction (Fig. 15) which in turn serves to rock the arm 171 so as to close the start switch 174. The start switch 174 is operatively connected to start the table driving motor 70 in a manner to be hereinafter described.

When the machine is in motion and it is desired to stop the machine, the start and stop lever 165 is shifted from broken line position 165a into full line position 165 which movement serves to rock the rock arm 171 in the opposite direction so as to actuate the stop switch 173 and thereby to stop the table traverse motor 70.

It is desirable to provide a suitable interlock between the table manual traverse mechanism and the power traverse mechanism so that manually operable hand wheel 40 will be automatically rendered inoperative during a power traversing movement of the table 11. This is preferably accomplished by providing an interlock between the start and stop lever 165 and the clutch 50 for controlling the manually operable traverse mechanism. The lever 53 (Fig. 15) is connected by means of a stud 177 with a slide rod 178. The slide rod 178 is supported adjacent to its

other end in a bearing 179. A flanged collar 180 is fixedly mounted on the right hand end of the rod 178. A compression spring 181 surrounds the rod 178 and is interposed between the bearing 179 and the collar 180. The spring 181 normally serves to maintain the clutch 50 in engagement with the clutch teeth 47 to render the manually operable traverse wheel 40 operative.

In order to interlock the table feed clutch actuating mechanism with the clutch for controlling the manual traverse mechanism, the rock shaft 166 is provided with a rearwardly extending arm 182. A pivotally mounted latch arm 183 is pivotally supported on a stud 184. The arm 183 is provided with a notch 185 which is arranged to engage the flange collar 180 when it is desired to lock the manual traverse clutch 50 out of engagement. A tension spring 186 is provided normally to maintain the latch arm 183 in engagement with the flanged collar 180.

In order to actuate the latch arm 183, the arm 182 is provided with a stud 187 which engages a cam surface 188 formed on the latch arm 183. In the position of the parts (Fig. 15), the stud 187 engaging the cam 188 serves to hold the latch arm 183 in an inoperative position. When the start and stop lever 165 is moved in a counterclockwise direction into position 165a to start a grinding operation, the stud 187 rides down the cam face 188 and the released tension of the spring 186 rocks the latch arm 183 in a counterclockwise direction. At the same time the arm 182 engages and moves the collar 180 together with the rod 178 toward the left (Fig. 15) so as to rock the arm 53 and the arm 51 in a counterclockwise direction and thereby to disengage the clutch member 50 so as to render a manually operable traverse wheel 40 inoperative during a power reciprocation of the work table 11.

It is desirable to hold the latch member 183 in an inoperative position during a continuous picker infeed during a plunge-cut operation so that the table 11 can not be traversed. In order to accomplish this result, the control lever 115 is provided with a stud 191 having a downwardly projecting lug 190 which is arranged in the path of a collar 192. The collar 192 is mounted on the right hand end of a slide rod 193 (Fig. 9). A collar 194 is fixedly mounted on the left hand end of the rod 193 and is arranged in the path of a downwardly projecting stud 195 on the latch arm 183. The lever 115 is provided with an adjustably mounted stud 196 which is arranged in the path of a spring pressed knob 250. The spring pressed knob 250 is operatively connected to actuate a normally open limit switch 197 when it is desired to provide a continuous picker infeed of the grinding wheel for a plunge-cut grinding operation.

When the control lever 115 is in a vertical position, it may be swung in a clockwise direction (Fig. 9) so that a detent 198 moves into engagement with a notch 199. A pair of notches 199a and 199b are provided to receive the detent 198 when the control lever 115 is swung to either a grinding or a truing position. A pair of stop pins 255 and 266 are provided (Figs. 5 and 22) to limit the rotary movement of the lever 115 and dial 116. During the swinging movement of the control lever 115 on the stud 117, the stud 196 moves the spring pressed switch actuating knob 250 toward the left to close the normally open limit switch 197. At the same time the downwardly projecting lug 190 moves the slide rod 193 toward the

right (Fig. 9) to move the collar 194 into engagement with the stud 195 and thereby to hold the latch member 183 in an inoperative position such as that shown in Fig. 15 during a plunge-cut grinding operation.

A suitable reversing mechanism is provided for reversing the direction of the movement of the table 11. This mechanism may comprise a manually operable reversing lever 200 which is pivotally supported by a horizontally projecting stud 201 which is carried by block 202. The block 202 is fixedly mounted on the upper end of a vertically arranged rock shaft 203. A compression spring 204 serves normally to hold the reversing lever 200 in the position illustrated in Fig. 18 with a stop screw 205 in engagement with the block 202. The reversing lever 200 is provided with an inwardly projecting lug 206 which is arranged in the path of a pair of table reversing dogs 207 and 208. The dogs 207 and 208 are adjustably supported by a T-slot formed in the front edge of the work table 11.

An arm 210 is fixedly mounted to the lower end of the vertical rock shaft 203 and is connected by means of a stud 211 with one end of a link 212. The other end of the link 212 is connected by a stud 213 with the actuating arm 214 of a reversing switch 215. The reversing switch 215 is operatively connected through an electronic control mechanism to be hereinafter described to reverse the direction of and to control the speed of rotation of the table driving motor 70.

The reversing lever 210 is provided with an arrow pointed projection 216 which is arranged to engage an arrow pointed spring pressed actuating plunger 217 for actuating a normally open limit switch 218 during table reversal to energize the picker feed solenoid 161 so as to provide an instantaneous engagement of the feed clutch 50 to produce an infeeding movement of the grinding wheel 33 at the ends of the table stroke during a traverse grinding operation. The energization of solenoid 161 rocks the arm 162 to withdraw the cam follower 158 from engagement with the cam 157. The released compression of the spring 156 will throw clutch 155 into engagement with clutch teeth 154 instantaneously to rotate shaft 141 to impart a feeding movement to the grinding wheel 33. The upward movement of the follower 158 opens a normally closed limit switch 163 to de-energize the solenoid 161 and the released tension of the spring 160 returns the follower 158 into operative engagement with the cam 157 which thereafter disengages the clutch 155.

It is desirable to provide a safety device to prevent the table 11 from over running at the ends of its stroke. This mechanism is preferably an electrically controlled mechanism comprising a pair of safety limit switches 220 and 221 which are arranged to be actuated by a pivotally mounted lever 222 which is pivotally supported on a stud 223. The stud 223 is fixedly supported relative to the base 10. An adjustably mounted stud 224 projects from the upper end of the lever 222 and is arranged in the path of a cam face 225 on the dog 207 and a cam face 226 on a safety dog 227 (Fig. 5). The lever 222 is provided with a switch actuating cam 228. The cam face 228 is arranged in the path of the actuating plungers of the limit switches 220 and 221. If the table 11 runs beyond its normal stroke, the cam face 225 or the cam face 226 will engage the stud 224 and rock the lever 222 to actuate either the switch 220 or the switch 221 which are operatively connected to stop the table driving motor. A

compression spring 229 is provided (Fig. 2) normally to hold the lever 222 in a central position.

In setting up the grinding machine and for certain grinding operations, it may be desirable to disconnect the picker feeding mechanism so that the wheel feed may be controlled manually or automatically as desired. As shown in Fig. 3, a selector switch 230 is provided which may be turned to an "off" position so as to render the automatic picker feed inoperative. If an automatic picker feed is desired the selector switch 230 is turned to an "on" position which closes a circuit to pass current through a limit switch 231 (Fig. 3).

In a traverse grinding operation, it may be desirable to provide an adjustable period of dwell at the ends of the table stroke. This is preferably accomplished by means of a pair of adjustable instantaneous reset electric time delay relays 235 and 236. The timer 235 is operatively connected to control the dwell at the left hand end of the table stroke and the timer 236 is arranged to control the dwell at the right hand end of the table stroke. The time relays 235 and 236 are connected respectively to normally open limit switches 237 and 238 which are arranged to be automatically closed when the control lever 115 is turned to a truing position so as to cut out table dwell during a grinding wheel truing operation.

The electric motor 70 is preferably controlled by any standard well known electronic control apparatus such as for example a Thy-Mo-Trol control apparatus manufactured by the General Electric Company.

35 Thy-Mo-Trol—Principle of operation

From the diagram shown in Fig. 24 it can be seen that a pair of tubes (tube 260 and tube 261) constitutes a full-wave rectifier which converts to direct current, the alternating current supplied by an anode transformer 262. The direct current is then fed through the armature of the motor 70. Likewise, tube 263 and tube 264 make up a full-wave rectifier, which supplies direct current to the shunt field of the motor 70. By varying the outputs of these two rectifiers, it is possible to control the operation of the motor 70. Its speed can be varied from zero, by armature-voltage control, up to maximum for which the motor 70 is designed to operate by field weakening.

50 Electronic control circuits

The means by which the output of the power rectifiers is varied is a group of radio-type control tubes 255, 266, 267, 268 and 269, whose basic circuit is shown in Fig. 24. Acting as amplifiers of current and voltage signals received from the motor circuit, these tubes supply the necessary direct current to the saturating winding of the saturable-core reactor in the resistance-reactance bridge which is used to vary the output voltage of the power rectifiers by the phase-shift method previously described. By varying the current in the saturating winding, the power tubes are turned on or off as required to give the desired motor performance.

To provide for the current-limit acceleration of the motor 70, a current transformer T6P1—TyP2—T6S is used. This has two primary windings T6P1 and T6P2 which are connected in the anode circuit of the two power tubes supplying current to the motor armature. The design is such that an alternating current voltage is produced in the secondary T6S, proportional to the current flowing through the thyratron tubes.

11

The alternating current voltage is rectified and connected into the circuit in such a way that when it reaches a value as determined by the setting of a potentiometer, it will have the effect of turning off the armature tubes, thus reducing the voltage on the armature and maintaining the current at a fixed maximum value.

If the control had been set to operate the motor 70 in the field-weakening range, the current-limit control acting through a suitable tube will maintain full field until the armature current starts to reduce. Thus, during acceleration under these conditions the motor will always accelerate from zero to base speed with full field. At this point, the field will be weakened gradually until the motor reaches the preset field weakened speed. Then the armature current will drop to the value necessary to drive the load.

The adjustment of the speed is controlled by two adjustable potentiometers—one controls armature voltage, the other controls field voltage. The potentiometers are operated from a single shaft and are arranged so that approximately half of the rotation of the adjusting knob will vary the armature voltage from approximately zero to maximum. Then the other potentiometer becomes effective, and further turning will tend to reduce the field voltage so that the motor speed can be increased to the value desired, up to the maximum for which the particular motor is designed to operate by field weakening.

To maintain the preset speed, it is necessary to hold armature counter-E. M. F. constant. This can be done by increasing the armature terminal voltage by an amount equal to the IR drop of the armature circuit. In this system, this is accomplished through the use of the same current transformer that controls the current limit. The circuit functions in such manner that as armature current increases, the thyratrons in the armature circuit are turned on, thus increasing the armature voltage. If the load increases, the circuit operates to increase the armature voltage proportionally, which thus acts to maintain the speed at its preset level. An adjustable potentiometer used in the circuit makes it possible to maintain essentially constant speed from no load to full load for any given speed setting, or to provide a drooping speed characteristic where desirable.

When the start and stop lever 115 is shifted to actuate the starter switch 174, the motor 70 will be accelerated rapidly and smoothly by current limit as described above until it reached a speed corresponding to the setting of the speed-adjusting potentiometer. The motor 70 will then maintain this speed closely, irrespective of variations in load, within the limits of the IR-drop-compensation feature. When the stop button 173 is pressed, the anode contactor will be dropped out and a resistor will be connected across the armature to bring the motor 70 to a quick stop as full field is applied. The substitution of a magnetic-reversing switch for the anode contactor makes it possible to reverse quickly the direction of rotation by current-limit regeneration of the motor 70.

This control apparatus is interconnected with the switches above described and the control apparatus to be hereinafter described. An adjustable potentiometer 241 is provided for controlling the speed of the motor 70 during a grinding operation. An adjustable potentiometer 242 is similarly provided independently to control the

12

speed of the table 11 so as to provide a very slow traversing movement thereof during a grinding wheel truing operation. A transfer switch 243 is provided which is interconnected with the potentiometers 241 and 242. The transfer switch 243 is normally held in a position to render the potentiometer 241 operative. The transfer switch 243 is operatively connected to be actuated by the control lever 115 so that when the control lever 115 is shifted to a grinding wheel truing position a cam 247 on the inside of the dial 116 actuates the transfer switch 243 so as to render potentiometer 242 operative to change from a grinding speed of the table 11 to a truing speed thereof. It should be readily apparent from the foregoing disclosure that the grinding speed of the table 11 may be regulated independently of the truing speed and by means of the transfer switch 243 the machine may be readily shifted from a grinding to a truing speed without disturbing the independent grinding and truing speed control devices.

It may be desirable in setting up the machine to jog the table 11 toward the right or toward the left that is to move the table by short increments to position a work piece 18 relative to the grinding wheel 33. This movement is preferably obtained by a jog switch 244 which is operatively connected in the electrical circuit to permit a jogging movement of the table toward the right. A jogging switch 245 is provided for facilitating a jogging movement of the table toward the left.

The dial 116 which is actuated by the control lever 115 is provided with a cam 247 which is arranged in the path of a plurality of spring pressed plungers 248, 249, 250, 251 and 252. These spring pressed plungers are arranged respectively to actuate the limit switches 231, 243, 197, 237 and 238 when the control lever 115 is moved in a counterclockwise direction (Fig. 5) to shift from a grinding to a truing position. When the control lever 115 is shifted to a truing position, the cam 247 serves to open the normally closed limit switch 231 to render the picker feeding mechanism inoperative, to shift the double throw transfer switch 243 so as to render the potentiometer 241 inoperative and to render the truing potentiometer 242 operative, closes normally open limit switch 197 to energize the picker feed solenoid 161, closes normally open limit switches 237 and 238 to render the electric time dwell relays 235 and 236 in operative during a grinding wheel truing operation. It will be readily apparent that these cam actuated limit switches serve as interlocks to prevent table dwell during a wheel truing operation, to prevent a continuous picker feed during truing and automatically to shift the table speed from a grinding to a truing speed through the potentiometers 241 and 242. At the same time the lever 115 is shifted, the slidably mounted clutch member 102 is shifted longitudinally to move the clutch member 100 into engagement with the clutch teeth 99 so as to automatically throw in the gears 92, 93, 104 and 105 thereby to shift the mechanical drive mechanism from a high speed to a low speed during a grinding wheel truing operation. Similarly when the control lever 115 is shifted from a truing to a grinding position the cam 247 is moved out of engagement with the spring pressed plungers 248, 249, 250, 251 and 252 to allow the switches to resume their former positions during a plunge-cut or a traverse grinding operation.

When the control lever 115 is in a vertical position such as shown in Fig. 5 the parts are set for

a plunge-cut grinding operation. Both of the clutches 99-100 and 107-108 are disengaged and a picker feed may be obtained by rocking the control lever 115 in a clockwise direction (Fig. 9) which serves to actuate the limit switch 197. The limit switch 197 being connected in a manner above described to provide a continuous picker infeed of the grinding wheel 33.

The operation of the electrically operated cylindrical grinding machine will be readily apparent from the foregoing disclosure. Assuming all the adjustments have been previously made, the wheel drive motor 34 is started by pressing the push button starter switch 39. The work drive motor 19 is then started by actuating the push button starter switch 20. With the control lever 115 in a central position (Fig. 1) a plunge-cut grinding operation may be obtained by rocking the control lever 115 toward the operator, that is, in a clockwise direction (Fig. 9) to actuate the switch 197 and thereby to start a continuous reciprocation of the feed pawl 138 to provide a continuous intermittent picker feed to grind the work piece 18 to the desired and predetermined extent.

If it is desired to set the machine up for a traverse grinding operation the table dogs 207 and 208 are adjusted to give the desired reciprocatory stroke of the table 11. The control lever 115 may be then rotated in a clockwise direction into a grinding position to move the clutch member 108 into engagement with the clutch teeth 107 so as to reciprocate the table at a relatively high speed for a traverse grinding operation. The start and stop lever 165 is then shifted toward the right (Fig. 1) to start the table drive motor 70. The speed of table 11 may be precisely regulated by adjustment of the potentiometer 241. An adjustable dwell may be obtained at either or both ends of the table stroke comprising electric timers 235 and 236 which may be adjusted to produce a dwell of a desired and predetermined extent.

When it is desired to true the grinding wheel, the control lever 115 is rocked in a counterclockwise direction into a truing position so that the clutch member 100 engages the clutch teeth 99 so as to traverse the table 11 at a relatively slow truing speed which may be precisely adjusted and controlled by the potentiometer 242. Movement of the control lever 115 to a truing position serves to automatically actuate the table double throw transfer switch 243 so that the speed control of the motor 70 is shifted from potentiometer 241 to 242. Movement of the control lever 115 into a truing position also serves to actuate the limit switches 237 and 238 to cut out the electric timers 235 and 236 thus eliminating table dwell at the ends of the stroke during a grinding wheel truing operation.

After the control lever 115 has been set in either a grinding or a truing position, the table may be set in motion by shifting the start and stop control lever 165. The start and stop lever 165 serves to actuate the starter switch 174 to start the rotation of the work driving motor 70.

The selector switch 230 permits the operator to render the power infeeding mechanism inoperative to facilitate a manual feeding of the grinding wheel if desired. When the selector switch 230 is in an "on" position the power infeeding mechanism is rendered operative and a continuous plunge-cut feed or an intermittent traverse feed may be obtained as desired.

Table jogging switches of the push button type are provided, push button switch 244 serving to

jog the table 11 toward the right and push button switch 245 serving to jog the table toward the left.

The jogging button 24 is provided to facilitate jogging the work drive motor 19 if desired in a setting up operation. A reversing switch 23 is provided whereby the work drive motor 19 may be readily reversed to reverse the direction of rotation of the head stock when desired. The speed control or potentiometer knob 22 is provided for precisely adjusting and regulating the speed of the head stock motor 19 so as to produce the desired speed of the work piece 18 during a grinding operation.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings, is to be interpreted as illustrative and not in a limiting sense.

I claim:

1. In a grinding machine having a base, a transversely movable wheel slide, means rotatably to support a grinding wheel on said slide, a longitudinally reciprocable table, a reciprocating mechanism therefor including a variable speed reversible electric motor, driving connections between said motor and table, an electronic control apparatus to control said motor so as to produce either a relatively high speed reciprocation of the table for a grinding operation or a relatively slow speed for a truing operation, table actuated means to reverse said motor, a control lever for said driving connections, independent manually operable electrical control means operatively connected with said control apparatus to adjust and regulate the speed of said motor for a grinding and for a truing speed, and independent means actuated by and in timed relation with said control lever to render either of said speed adjusting means operative.

2. In a grinding machine having a base, a transversely movable wheel slide, means rotatably to support a grinding wheel on said slide, a longitudinally reciprocable table, a reciprocating mechanism therefor including a variable speed reversible electric motor, driving connections between said motor and table, table actuated means to reverse said motor, said motor and driving connections being arranged to produce either a relatively high speed reciprocation of the table for a grinding operation or a relatively slow speed for a truing operation, a control lever for said driving connections, independent manually operable means independently to adjust and regulate the speed of said motor for a grinding and independent manually operable means independently to adjust and regulate the speed of the motor for a truing speed, and independent means actuated by and in timed relation with said control lever to render either of said speed adjusting means operative.

3. In a grinding machine having a base, a transversely movable wheel slide, means rotatably to support a grinding wheel on said slide, a longitudinally reciprocable table, a reciprocating mechanism therefor including a variable speed reversible electric motor, means including a reversing lever to reverse said motor, driving connections between said motor and table, said motor

and driving connections being arranged to produce either a relatively high speed reciprocation of the table for a grinding operation or a relatively slow speed for a truing operation, a control lever for said driving connections, a pair of independently adjustable electric speed control means independently to adjust and regulate the speed of said motor for a grinding and independently to adjust and regulate the speed of said motor for a truing operation, and manually operable independent means actuated by and in timed relation with said control lever to render one or the other of said speed control means operative.

4. In a grinding machine having a base, a transversely movable wheel slide, means rotatably to support a grinding wheel on said slide, a longitudinally reciprocable work table, a reciprocating mechanism therefor including a variable-speed reversible electric motor, a multi-speed change gear mechanism connecting said motor with said table which is arranged to produce either a relatively high speed reciprocation of the table for a grinding operation or a relatively slow speed reciprocation of the table for a truing operation, means including adjustable dogs on said table for reversing said motor, a control lever to actuate said change gear mechanism, a pair of independent manually operable rheostats independently to adjust and regulate the speed of said motor for a grinding and independently to adjust and regulate the speed of said motor for a truing speed, and independent means actuated by and in timed relation with said control lever to render one or the other of said speed control means operative when said lever is shifted to a grinding or a truing position.

5. In a grinding machine having a base, a transversely movable wheel slide thereon, means rotatably to support a grinding wheel on said slide, a longitudinally reciprocable work table, a reciprocating mechanism therefor including a variable-speed reversible electric motor, a multi-speed change gear mechanism including a pair of clutches to connect said motor with said table, one of said clutches being arranged to produce a relatively high speed reciprocation of the table for a grinding operation and the other clutch being arranged to produce a relatively slow speed reciprocation of the table for a truing operation, means including adjustable dogs on said table for reversing said motor, a control lever to actuate both of said clutches, a pair of independent manually adjustable electric speed control means independently to adjust and regulate the speed of said motor for a grinding and independently to adjust and regulate the speed of said motor for a truing speed, and means including a switch which is actuated by and in timed relation with said control lever to render one or the other of said speed control means operative when said lever is shifted to a grinding or to a truing position.

6. In a grinding machine having a base, a transversely movable wheel slide thereon, means rotatably to support a grinding wheel on said slide, a longitudinally reciprocable table, a reciprocating mechanism therefor including a variable-speed reversible electric motor, a two-speed change gear mechanism including a pair of clutches connecting said motor with said table, one of said clutches being arranged to produce a relatively high speed reciprocation of the table for a grinding operation and the other clutch being arranged to produce a relatively

slow speed reciprocation of the table for a truing operation, table actuated means for reversing said motor, a control lever to actuate both of said clutches, a pair of independent manually adjustable electric speed control means independently to adjust and regulate the speed of said motor for a grinding and independently to adjust and regulate the speed of said motor for a truing speed, and means including a transfer switch which is actuated by and in timed relation with said control lever to render one or the other of said speed control means operative when said lever is shifted to a grinding or a truing position.

15. 7. In a grinding machine having a base, a transversely movable wheel slide thereon, means rotatable to support a grinding wheel on said slide, a longitudinally reciprocable work table, a reciprocating mechanism therefor including a variable-speed reversible electric motor, a two-speed change gear mechanism including a pair of clutches connecting said motor with said table, one of said clutches being arranged to produce a relatively high speed reciprocation of the table for a grinding operation and the other clutch being arranged to produce a relatively slow speed reciprocation of the table for a truing operation, means including adjustable table dogs and a switch to reverse said motor, a manually operable control lever to actuate both of said clutches, a pair of independent manually adjustable rheostats independently to adjust and regulate the speed of said motor, one rheostat serving to adjust the speed of the motor for a grinding operation and the other rheostat serving to adjust the speed of the motor for a truing speed, and means including a transfer switch which is actuated by and in timed relation with said control lever to render one or the other of said rheostats operative when said lever is shifted to a grinding or a truing position.

8. In a grinding machine as claimed in claim 1, the combination with the parts and features therein specified, of means including an independent electrical time delay relay to cause an adjustable dwell during reversal of the table drive motor so as to produce a table dwell at either or both ends of the reciprocatory stroke of said table, a pair of independent limit switches to render said relays inoperative, and means actuated by and in timed relation with said control lever to actuate said limit switches when the control lever is shifted to a truing position so as automatically to cut-out table dwell during a grinding wheel truing operation.

9. In a grinding machine having a base, a transversely movable grinding wheel slide, means rotatably to support a grinding wheel on said slide, a longitudinally reciprocable work table, means including a table actuated reversing lever to reciprocate said table, means to feed said slide, a pawl and ratchet mechanism to actuate said feeding means, means including a normally engaged clutch continuously to actuate said pawl, a normally inoperative cam and a follower intermittently to disengage said clutch to provide a plunge-cut feeding movement of the slide, yieldable means normally to maintain said follower engaged with said cam, an electric solenoid to shift said follower out of operative engagement with said cam, and a limit switch actuated by and in timed relation with said table reversing lever to energize said solenoid and thereby shift said follower out of operative engagement with said cam to produce an intermittent infeeding

of the grinding wheel during reversal at the ends of the table stroke for a traverse grinding operation.

10. In a grinding machine having a base, a transversely movable wheel slide thereon, means rotatably to support a grinding wheel on said slide, a longitudinally reciprocable work table, means including adjustable dogs on said table and a reversing lever to reciprocate said table, means including a nut and screw mechanism to feed said slide, a pawl and ratchet mechanism to feed said slide, a pawl and ratchet mechanism to rotate said screw, means including a normally engaged clutch continuously to actuate said pawl, a normally inoperative cam and a follower intermittently to disengage said clutch to provide a continuous intermittent plunge-cut feeding movement of said slide, yieldable means normally to maintain said follower engaged with said cam, an electrical solenoid to shift said follower out of engagement with said cam, and a limit switch actuated by movement of said table reversing lever to energize said solenoid and thereby to shift said follower out of operative engagement with said cam to provide an intermittent feeding movement of the grinding wheel during reversal for a traverse grinding operation.

11. In a grinding machine having a base, a transversely movable wheel slide thereon, means rotatably to support a grinding wheel on said slide, a longitudinally reciprocable table, means including adjustable dogs on said table, and a reversing lever to reciprocate said table, means including a nut and screw mechanism to feed said slide, a pawl and ratchet mechanism to rotate said screw, a plunge-cut feeding mechanism including a normally engaged clutch continuously to actuate said pawl, a normally inoperative cam and a follower intermittently to engage said clutch to provide a continuous intermittent plunge-cut feed of said slide, yieldable means normally to maintain said follower engaged with said cam, an electrical solenoid to shift said follower out of engagement with said cam, and a traverse-grinding feeding mechanism including a limit switch actuated by movement of the table

reversing lever to energize said solenoid and thereby to shift said follower out of operative engagement with said cam to provide an intermittent movement of the grinding wheel during reversal at the ends of the table stroke for a traverse grinding operation.

- 5 12. In a grinding machine having a base, a transversely movable wheel slide thereon, means rotatably to support a grinding wheel on said slide, a longitudinally reciprocable table, means including a nut and screw mechanism to feed said slide, a pawl and ratchet mechanism to rotate said screw, a plunge-cut feeding mechanism including a normally engaged clutch continuously to actuate said pawl, a normally operative cam and a follower intermittently to engage and disengage said clutch to provide a continuous intermittent plunge-cut feed of said slide, yieldable means normally to maintain said follower engaged with said cam, an electrical solenoid to shift said follower out of engagement with said cam, a traverse grinding feeding mechanism including a limit switch actuated by movement of the table reversing lever to energize said solenoid and thereby to shift said follower out of operative engagement with said cam to provide an intermittent movement of the grinding wheel during reversal for a traverse grinding operation, and means including a selector switch to render either said plunge-cut or said traverse grinding feed operative.
